UNITED STATES PATENT OFFICE.

CHARLES W. LYNCH, OF PERRY, OKLAHOMA, ASSIGNOR TO PICKERING LUMBER COMPANY, OF KANSAS CITY, MISSOURI, A CORPORATION OF DELAWARE.

DERRICK-TOP ASSEMBLY.

Application filed August 18, 1926. Serial No. 129,877.

This invention relates to tops for compression type wood derricks, and my object is to produce an efficient and safe derrick at less assembly cost than the conventional derrick of this type. With the type in general use, it is customary to provide top leg sections of materially larger cross section than the other sections of the legs, to allow for cutting and fitting for the accommodation 5 of the top assembly, without undue weakening of the general structure, the use of enlarged leg members being also necessary, as with such structures it is impracticable to use girts as close to the top of the leg members as desirable to provide maximum strength and rigidity.

My object is to provide a construction which not only permits girts to be employed at the upper extremities of the legs but also 20 permits of the use of topmost leg members of the same cross sectional area and form as the underlying leg sections without any sacrifice of strength or rigidity. My improved construction also provides for the use of top 25 elements, known in the oil field as deadwoods and crossheads or headers, with which no care need be exercised or time wasted in the setting of such elements. Furthermore the improvement makes practical the use of 30 I-beam headers to sustain the load and of flanged plates to transmit the load to and upon the end extremities of the legs and guard against separating or spreading movement of the headers and deadwoods, and 35 thus provide for an equitable distribution of the load on the entire derrick in a simple and efficient manner.

With the object set forth in view, the invention consists in certain novel and useful 40 features of construction and organization as hereinafter described and claimed; and in order that it may be fully understood, reference is to be had to the accompanying drawings, in which:

45 Figure 1 is a top view of the upper part of a derrick embodying the invention.

Figure 2 is a section on the line II—II of Figure 1.

50 Figure 3 is a section on the line III—III of Figure 1.

Figure 4 is a side elevation of the upper end of the derrick.

Figure 5 is an enlarged vertical section on the line V—V of Figure 1.

55 Figure 6 is a detail perspective view of

one of the corner brackets employed in the support and assembly of the headers and deadwoods.

In the said drawings, where like reference characters identify corresponding parts in all of the figures, 1 indicates derrick legs, 2 horizontal girts extending from one leg to another, and 3 are the customary brackets used for connecting the adjacent ends of superposed leg members together, it being understood the legs are composed of a series of members arranged end to end, as customary in this type of derrick, the ends of the respective girts being bolted or otherwise secured to such brackets, it being noted in this instance that the leg members extending upward from brackets 3 are shown as of the same cross sectional area as where extending downward from said brackets, the use of relatively light topmost leg members being practicable because they are not weakened by cutting or recessing and because they are braced at their upper extremities by girts 2 abutting opposite leg members and secured thereto through the medium of angle brackets 4 secured to the upper ends of the leg members and projecting upward therefrom. Each of the angle brackets 4 accommodates a bearing plate 5 resting flatly upon an underlying leg, and the said plates are loosely connected to the respective brackets 4, as shown in Figure 5, to guard against misplacement, as the plates will operate efficiently if merely placed upon the ends of the leg members without being fastened in any way to the brackets 4. The plates are provided at their outer margins with flanges 6, and form supports for parallel I-beam headers 7, the headers bearing at the outer edges of their base flanges against the adjacent plate flanges, and the ends of the headers bearing against the other flanges of the same plates. The headers are thus prevented from endwise movement and from sliding outwardly. To prevent them from sliding inwardly and from tilting, and from moving upwardly, bolts 8 connect them through the web portions, with the brackets 4, as shown most clearly in Figure 2. They are also tied together and braced apart by a pair of deadwoods, each of which is arranged horizontally in the same plane as but crosswise with respect to the headers, and are tapered at the ends of their upper and lower sides so as to fit between the inwardly projecting 100 105 110 115

flanges of the headers and bear against the webs thereof, and said deadwoods are retained in position by bolts 10 which connect them with the corner brackets 4. It will be noted, at this point, that the I-beams where used on large derricks of this character and weighing several hundred pounds, can be readily placed in position by the usual gin pole apparatus (not shown) without the exercise of any particular care, because either side of the I-beams may be the top or bottom, and the same statement applies to the heavy deadwoods, as they will be so made that the holes therein will register with the holes of the corner brackets 4 designed for the reception of bolts 10, regardless of which beveled side is disposed uppermost. To still further stiffen and strengthen the structure, crossed turn-buckle tie rods connect the corner brackets 4 with the underlying set of corner brackets 3, the upper end of the said crossed braces being preferably hooked as at 12 into openings in brackets 4, the same openings of said brackets also forming anchorage points for the opposite ends of horizontal turn-buckle braces 13, as shown clearly by Figures 1 and 4.

It will thus be seen that the upper extremities of the legs of the derrick are efficiently braced from twisting and other movements, and that the same statement applies to the corner brackets 4, and that the headers and deadwoods are secured in place strongly and economically.

From the above description, it will be apparent that I have produced a top assembly for wood derricks of the compression type which possesses the features of advantage set forth as desirable in the statement of the object of the invention, and it is to be understood that changes properly falling within the principle of construction and mode of operation involved, may be made without de-

parting from the spirit and scope of the appended claims.

I claim:

1. A derrick comprising a set of four legs, right angle corner plates fitting respectively against the two outer sides of each leg and projecting thereabove, plates resting upon the upper ends of the legs within said brackets, a pair of parallel I-beams bridging the space between pairs of the posts and resting thereon, a pair of parallel deadwoods extending at right angles to and abutting said I-beams, means for securing the I-beams and deadwoods to said corner brackets, and compression means for bracing the plates, headers and deadwoods against relative spreading movement.

2. The combination in a derrick having four legs, of angle plate brackets secured to said legs at their upper extremities and projecting beyond such extremities, angle brackets secured to said legs in a lower plane than the first named brackets, horizontal girts between opposite legs and fastened to brackets in corresponding horizontal planes, crossed braces connecting the lower set and upper set of brackets, horizontal braces also connecting the upper set of brackets, plates fitting in said brackets and resting upon said legs, a pair of parallel I-beams fitting in a pair of said topmost brackets and resting upon a pair of said plates, and a pair of deadwoods extending at right angles to said I-beams and bearing at their ends against the web portions of said I-beams, and their upper and lower sides fitting against the adjacent flanges of the I-beams, and means for fastening the I-beams and deadwoods to the said uppermost set of brackets.

In witness whereof I hereunto affix my signature:

CHARLES W. LYNCH.
